SANITARY COMB

Charles J. Ward, Grasmere, N. Y.

Application February 10, 1936, Serial No. 63,090

2 Claims. (Cl. 132—19)

The primary object of this invention is to provide a cleaning device associated with a comb, which is operable to remove the dirt and foreign matter from the teeth of the comb, whereby the comb may be easily maintained in a sanitary condition.

A further object of the invention is to provide a device of the above-mentioned character, which is simple and durable in construction, reliable and efficient in use, inexpensive in cost of manufacture, and neat and compact so that it may be conveniently carried in the pocket or a lady's handbag.

Other objects and advantages of the invention will be apparent during the course of the following description.

In the accompanying drawing, forming a part of this specification and in which like numerals are employed to designate like parts throughout the same,

Fig. 1 is a side elevation of a comb, showing the cleaning device in inoperative position.

Fig. 2 is a similar view showing the cleaning device in operation.

Fig. 3 is a horizontal section taken on line 3—3 of Fig. 2.

Fig. 4 is a vertical section taken on lines 4—4 of Fig. 2.

Referring in detail to the drawing, wherein for the purpose of illustration I have shown a preferred embodiment of my invention, the numeral 10 denotes a comb having the usual teeth 11 and back 12. A cleaning bar 13 extends longitudinally of the comb and is provided with a plurality of apertures 14 to receive the teeth 11, which pass therethrough. The cleaning bar is movable vertically the full length of the teeth, and the edges of the apertures 14 scrape against the side of the teeth so as to remove the dirt

therefrom upon movement of the bar. On either end of the back 12 of the comb, an arched link 15 is pivotally mounted in a cut-out socket having side ears 16. An intermediate link 17 pivoted to the link 15, is joined to a similar link 18 which in turn is connected to the end of the bar 13.

When carried in the pocket or otherwise not in use, the bar and its associate links assume the positions shown in Figure 1 with the bar 13 lying against the back of the comb and the collapsed links 17 and 18 lying against the side of the comb. To utilize the bar 13 to clean the teeth 11, the lower ends of the links 18 are first swung outward and upward (Figure 1), and then the bar 13 is pushed downward until it assumes the position shown in Figure 2. Any dirt or grit which may have been caught between the teeth 11 will, during this movement of the bar 13, have been carried toward the ends of the teeth 11, and from the latter position they may be readily removed by means of a brush or the like.

Obviously, modifications in form and structure may be made without departing from the spirit and scope of the invention.

I claim:

1. The combination with a comb, of a cleaning bar having a plurality of apertures to receive the teeth of the comb, and a pair of hinged links connecting the ends of said cleaning bar to the back of the comb, whereby said cleaning bar is permitted to move vertically of the comb teeth.

2. The combination with a comb, of a cleaning bar having a plurality of apertures to receive the teeth of the comb, and a pair of hinged links connected to the ends of said cleaning bar, one of said links having its free end hingedly connected to the end of said cleaning bar, the other of said links having its free end hingedly connected to the end of the comb back.

CHARLES J. WARD.
